UNITED STATES PATENT OFFICE.

MARTIN WANNER, OF ROBINSON, ASSIGNOR OF ONE-HALF TO JOHN A. HALL,
OF AXIAL, COLORADO.

CAR-HEATER.

SPECIFICATION forming part of Letters Patent No. 374,766, dated December 13, 1887.

Application filed June 24, 1887. Serial No. 242,368. (No model.)

To all whom it may concern:

Be it known that I, MARTIN WANNER, a citizen of the United States, residing at Robinson, in the county of Summit, State of Colorado, have invented certain new and useful Improvements in Car-Heaters, of which the following is a specification, reference being had therein to the accompanying drawings.

My invention relates to improved means for heating railway-cars with air passed through a smoke-stack heater, through which is also passed the products of combustion from the engine-furnace, as well as the exhaust-steam from the cylinders.

The objects of my invention are to provide improved means for forcing the air from a blower through the heater and through the cars of the train, to provide improvements in the construction of the smoke-stack heater by which the air to be heated is exposed to a large area of heating-surface without obstructing the draft of the engine, and to provide improved means for automatically regulating and distributing the heat within the cars; and the improvement consists in certain constructions and combination of parts, hereinafter described and claimed.

In the accompanying drawings, Figure 1 is an elevation of a locomotive-engine and the forward end of a car with my improvements applied thereto. Fig. 2 is an enlarged elevation of the stack-heater partly broken away. Fig. 3 is a vertical section on line xx of Fig. 2. Fig. 4 is a horizontal section in line yy of Fig. 2. Fig. 5 is an enlarged longitudinal section through the air-pipe coupling. Fig. 6 is an enlarged elevation, with one side in section, of a thermostat for operating the valve of the heat-regulating and air-distributing valve. Fig. 7 is an enlarged vertical section of said valve. Fig. 8 is a side view of the blower and its engine.

The engine A is coupled to the tender and car B in the usual manner, and carries at the forward end of the boiler a blower, C, located behind the head-light and above the smoke-box. The blower C is driven, preferably, by an independent double-cylinder engine, c, connected with said blower, and the latter with the air-heating space within the stack-heater D by a pipe, C'. This stack-heater is formed

of an outer shell, d, and an inner shell, d', riveted to a cap, D', and head d^2 at their upper end and to a base, D ^{2} , and head d^3 at the lower end thereof. The heads d^2 d^3 are perforated to receive and support vertical tubes d^4 , arranged in concentric rings around a larger central tube, d^5 . A deflector-plate, d^6 , is located above and upon the sides of an air-induction opening, D ^{3} , with which the pipe C' is connected. Perforations d^7 are in the upper end of the inner shell, d', to admit air from the space between inner and outer shells to the space around the tubes d^4 d^5 , and an air-eduction pipe, D ^{4} , at the lower end of the stack-heater passes through the inner and outer shells and allows the heated air to escape from the interior of the heater to the hot-air conduit E, passing alongside of the engine.

F is an automatic coupling, composed of an enlarged head, F', having ring-abutments f^1 cast upon its inner surface, a valve, F ^{2} , pivoted at its upper end to close against the inner face of the abutments f^1 , a gland, F ^{3} , fitted into the head F', and a tubular plug-section, F ^{4} , secured to the end of a connecting conduit-section, E', which passes beneath the cars of the train. When the plug-section F ^{4} is inserted into the head F', the valve F ^{2} is opened, and when the said plug-section is withdrawn the valve will automatically close to shut off the escape of heat from the heater.

The conduit-sections E' pass beneath the cars, and are each provided at their ends with a heat-regulating and air-distributing valve, G, located in the ends of the cars, and connect the conduit-sections E', through an opening, g, in the valve-easing G', with the heating-pipes H, passing along the sides of the car through openings g' in said valve-easing. The valve G is cylindrical and fits snugly in a corresponding opening in the valve-easing.

Triangular ports g^2 in the valve G are located opposite the opening g' in the valve-easing when the valve is down and said openings are open; but they become closed when the valve is raised. The triangular shape of the ports g^2 , with their base uppermost, causes the valve to close the opening more rapidly at the beginning of its movement, and thus quickly act to shut off the heat from the interior of the car when it has become overheated. The heat

is thus regulated and the valve is operated automatically by a thermostat consisting of a tube, I, having a bulb, I', at its lower end, and is partly filled with mercury. The upper end 5 of said tube I is fitted with a piston, I², connected by a cross-head, I³, and rods I⁴ I⁵ with the valve G, which is thus actuated by the expansion of the mercury within the tube. The valve falls by its own weight when the mercury contracts by the reduction of temperature 10 within the car, and opens communication between the heat-distributing pipes and the hot-air conduits.

The air taken from the front of the engine 15 enters the heater D at the opening D¹, and is first deflected downwardly by the plate d⁶, then passes up through the annular space between the inner and outer shells, d d', and is admitted through the perforations d⁷ to the 20 space within the heater surrounding the tubes d' d⁸ and discharged through the pipe D⁴ at the lower end of the heater. The tubes pass vertically through the stack-heater, and offer no obstruction to the direct upward passage of 25 the products of combustion or to the escape of the exhaust-steam from the cylinders. The blower forces the air through the heater and conduit pipes under sufficient pressure to insure a forced circulation and distribution of

the air through and away from the heater, and, 30 being driven by a separate engine, the air is forced through the heater and conduits to the cars both when the train is moving and when it is at rest.

I am aware that air has been passed through 35 a coil within a smoke-stack of a locomotive, has been heated therein, and has been drawn and forced therefrom by means of a blower, and do not claim, broadly, said devices; neither do I claim thermostatic tubes to control valves. 40

What I claim as my invention is—

In combination with a blower and its engine located upon a locomotive, a car-heater forming a part of the stack of said locomotive, and consisting of an outer shell having an inlet in 45 its side and an inner shell having an outlet-opening in its side for the passage of air, perforated heads and tubes connecting them, a deflector-plate, d⁶, between the shells over the inlet, and the inner shell provided with perforations d⁷, and pipes leading said air to the 50 cars of a train, substantially as described.

In testimony whereof I affix my signature in presence of two witnesses.

MARTIN WANNER.
